(57) **CLAIM**

The ornamental design for a knife sharpener, as shown and described.

DESCRIPTION

FIG. 1 is a front, left, top perspective view of a knife sharpener, showing my new design;

FIG. 2 is a rear, right, bottom perspective view thereof;

FIG. 3 is a front elevational view of the reduced scale thereof;

FIG. 4 is a rear elevational view of the reduced scale thereof;

FIG. 5 is a left side view of the enlarged scale thereof;

FIG. 6 is a right side view of the enlarged scale thereof;

FIG. 7 is a top plan view of the reduced scale thereof;

FIG. 8 is a bottom plan view of the reduced scale thereof;

FIG. 9 is an enlarged view of detail 9 in FIG. 3;

FIG. 10 is an enlarged view of detail 10 in FIG. 4; and,

FIG. 11 is an enlarged view of detail 11 in FIG. 8.

The dashed broken lines in the figures are for the purposes of illustrating portions of the knife sharpener and form no part of the claimed design.

The dash-dot-dash broken lines are for notating enlarged views and form no part of the claimed design.
